UNITED STATES PATENT OFFICE.

LISLE T. ARGO AND HARRY L. VINES, OF LOS ANGELES, CALIFORNIA.

BURNER.

Application filed March 7, 1927. Serial No. 173,238.

This invention relates to a burner adapted for the combustion of oil, gas, or both of these fuels. It is more especially suitable for handling large quantities of fuel, and air or steam under pressure is employed to aid in the induction of the fuel.

It is the primary object of this invention to provide a novel form of adjustable nozzle wherein the gaseous fuel is introduced to an annular opening surrounding the air or steam inducing nozzle. In addition to the broader objects of this invention there are certain details of structure whereby a simple, economical, and efficient burner is obtained.

These objects together with other objects and corresponding accomplishments are obtained by means of the embodiment of our invention illustrated in the accompanying drawing, in which:

Fig. 1 is an axial section through a complete combination burner; Fig. 2 is an elevation partly in section as seen on a plane at right angles to Fig. 1 showing the mixing member; and Fig. 3 is a section as seen on the line 3—3 of Fig. 1, with portions of the shutter broken away.

Referring more particularly to the drawing and especially Fig. 1, an induction nozzle or tube A is shown through which steam or air is introduced under pressure and through which oil or fluid may be induced. Mounted over the end of the induction tube is an air shell B. Adjustably mounted upon the end of the air shell is the mixing member C provided with a jacket through which gas is supplied. The gas enters the tubular portion of the mixing chamber through an annular orifice provided between the mixing member and the shell.

The oil unit comprises a tube 4 secured to a coupling member 5 having an extension to receive a pipe 6 through which gas or steam is supplied. At the end or rear of the coupling member 5 is a stuffing box or gland 7. At the front of the tube 4 is a conical nozzle 8 secured thereto by a suitable thread. Extending through the center of the tube 4 is an oil tube 9 having a conical nozzle 10 secured to the forward end thereof and connected within the nozzle 8 to provide a space around the nozzle 9 for the passage of gas or steam. The enlargement 11 may be of spider form to hold the ends of the tube 9 securely in position. The rear of tube 9 extends through the stuffing box 7 and coupling member 12 to a fitting 13. Fitting 13 has one branch con-

nected to a pipe 14 for supplying oil. The end of tube 9 has lateral ports and secured thereto is a stem 15 with a hand wheel 16 whereby the tube 9 may be adjusted forwardly and backwardly within the tube 4 and thereby the area of the space through which air or steam passes to the end of the nozzle 8 from which it is projected may be adjusted. Obviously, steam or air introduced through pipe 6 will induce oil through the nozzle 8.

The shell B comprises a bell shaped member 17 having the large end open and an arm 18 extending thereacross to the center at which there is a hub 19 having a bore internally threaded to engage with the threads on fittings 5 to provide for longitudinal adjustment with respect to the tube and thereby enable adjustment of the nozzle 8. There are bosses at the outer edge to provide for pivot pins 20. Pivotaly mounted upon each pin is a quadrant shutter member 21 having a finger hold 22 projecting therefrom. The shutters 21 have a sufficiently tight mounting so they will remain in any position into which they are swung. The forward end or throat of the shell is bevelled to provide one wall of an annular orifice. There is an enlargement 23 around the reduced end of the shell exteriorly threaded to serve as a mounting for the mixing member C. It will be noted that the air shell is beyond the end of the nozzle 8.

The mixing member comprises a tubular portion 24 having an inner end opposing the end of the air shell and forming therewith the annular orifice 25. Surrounding the tubular member is a jacket wall 26, projecting rearwardly beyond the orifice end of the tubular member and internally threaded to engage the enlargement 23. Opening into the jacket 95 is an inlet for gas indicated by 27.

The burner is mounted in position within a draft opening in a furnace. The pipe leading to the opening 27, is connected to the gas supply. The pipe 6 is connected either to a compressed air supply line or to a steam line. Pipe 14 may be connected to an oil supply line. The burner is then in condition to be used as a combination burner. The steam passing through nozzle 8 will vaporize the oil. The gas passes through the annular orifice 25 and induces air through shell B. The size of the orifice 25 may be adjusted by rotating the shell B. The amount of air passing through the air shell can also be adjusted by the shutters 21. The amount of oil is adjusted by means of the hand wheel 16 which locates the

nozzle 10 longitudinally within nozzle 8. The projected fluids comprise a stream having a core including air which is surrounded by an envelope of gas. This issues from the 5 burner and draws with it an outer envelope of air. Obviously the burner may be used as a gas burner alone by closing the supply line for oil and steam. In this case the gas induces the air and a stream having an air core 10 and gas envelope is provided.

The burner is an induction burner and the inductive action depends upon the length of the shell C, the freedom of the path of flow of air and the port area of the air inlets. In 15 the present construction, there is a direct substantially straight line flow, the cross section progressively decreasing toward the throat to provide a passage of little impedance to the flow of air, the enlarged end of the bell 20 with air ports results in an intake of a large volume of air at atmospheric pressure. The velocity of the induced air is increased toward the throat with a maximum at the annular gas opening 25 so as to induce a large volume 25 of air commensurate with the volume of gas entering the port 25, the latter being adjustable to permit a proper adjustment of the air-gas ratio.

What we claim is:

30 1. In a burner, an injector tube normally fixed in position and having a nozzle, an air shell about said tube, said shell being of reduced diameter at said nozzle forming therewith an induction nozzle and having an annular enlargement on the reduced end provided with a thread, the end of said shell forming a wall of an annular orifice inclined outwardly, a mixing member having a tubular portion serving as a continuation of said 40 reduced end and mounted upon the threaded enlargement whereby to adjust said orifice opening.

2. In an induction burner, an air shell of bell shape progressively decreasing in cross-section toward the throat and having air openings at the large end in communication with the atmosphere and facing in the direction of the axis of said shell, a circumferential gas supply member mounted on and having an annular port communicating with the bore of said shell and directing gas thereto in the direction of flow of air to form an envelope surrounding the air stream, and a mixing chamber constituting a continuation of

the bore of said shell of the same diameter 55 and into which the envelope of gas and core of air pass.

3. In an induction burner, an air shell of bell shape progressively decreasing in cross-section toward the throat and having air inlets at the large end open to the atmosphere 60 and facing in the direction of the axis of said shell, a circumferential gas supply member mounted on and having an annular port communicating with the bore of said shell and supplying 65 gas thereto in the direction of flow of air to form a tubular envelope of gas surrounding the air stream, said gas supply member being adjustable on said shell to vary the annular port and control the air-gas ratio.

4. In an induction burner, an air shell of bell shape progressively decreasing in cross-section toward the throat and having air inlets at the large end open to the atmosphere 75 and facing in the direction of the axis of said shell, a tubular gas supply member mounted over said throat and having an adjustable annular orifice for the introduction of an envelope of gas in the direction of flow of air and about the air passing through said throat, 80 and a mixing chamber constituting a continuation of said throat of the same diameter beyond said orifice and of substantial length.

5. In a burner, an injector tube normally fixed in position having a nozzle, an air shell 85 about said tube, said shell being of bell shape decreasing progressively in cross-section toward the throat and having air inlets at the large end open to the atmosphere and facing the direction of the axis of said shell, said 90 shell being movable for longitudinal adjustment with respect to said tube, the end of said shell projecting beyond said nozzle and forming therewith an induction nozzle and having an end wall forming a part of an annular 95 orifice outwardly inclined, a tubular mixing member mounted on the end of said shell and having a jacket with a gas inlet, said member having an end wall forming the other portion of said annular orifice and being movably mounted on said shell for longitudinal adjustment of said orifice.

In witness that we claim the foregoing we have hereunto subscribed our names this 11th day of August, 1926.
